PLASTIC SHEET MATERIAL OR SIMILAR ARTICLE

Arno H. Scheiding, Rowayton, Conn., assignor to L. E. Carpenter & Company, Inc., Wharton, N. J., a corporation of New Jersey

Application September 3, 1957, Serial No. 47,586

Term of patent 14 years

(Cl. D87—3)

Fig. 1 is a plan view of a piece of plastic sheet material embodying my new design; and

Fig. 2 is a sectional view taken on the line II—II of Fig. 1.

I claim:

The ornamental design for a plastic sheet material or similar article, substantially as shown.
